UNITED STATES PATENT OFFICE

JOSEPH GOUGH, OF NEWARK, NEW JERSEY, ASSIGNOR TO GOUGH STEMMING MACHINE CORPORATION, A CORPORATION OF NEW JERSEY

LEAF STEMMER

Application filed August 10, 1925. Serial No. 49,208.

My invention relates to apparatus for stemming leaves, that is to say, removing a considerable part of the large main veins from the blades. It is especially intended for tobacco leaves, and the invention is especially applicable to continuous machines, in contradistinction to machines of the intermittently operating type.

As simplified by this invention, the butting mechanism, which is frequently used to clean the butts of the stems preliminary to stemming, consists of a single butting roll operating in conjunction with a flat surface. Card clothing with a co-acting plate close to or bearing against the ends of the clothing teeth or wires, is preferably used to propel the leaves sidewise and hold them against endwise movement during the butting operation. Preferably also a pair of blade-gripping belts are used in conjunction with the card clothing.

The mechanism for grabbing and pulling out the stems or veins from the blades consists of a pair of endless belts running at a large angle to the conveyor mechanism which carries the leaves through the machine. These may run at a full right angle to the conveyor mechanism, or at less than a right angle as for a purpose later described. I find that such mechanism, which takes hold of more and more of the stem or vein as the latter is pulled out of the blade, has considerably less tendency to break the stems than the jaws and rollers that have been used heretofore and which take hold on only a short length of stem. The material of the belts, and likewise the facing of their supporting pulleys, may be soft and elastic so as to compensate for differences in size of the stems and the decreasing thickness of each stem toward the point of the leaf to secure a substantial grip on the stems throughout the whole or a long length of each one. While stemming, the blades of the leaves may be retained or stripped by a second card clothing which also may be overlaid with a plate as at the butting brush. Preferably however, I use upper and lower cooperating card clothing, and I have made special provision for cleaning the upper card as here-

after explained. Separate units of card clothing at the butting and stemming stations are preferred to one extended unit for both stations, both for constructional reasons and because it is preferable that the card at the stemmer be located somewhat back of the butting card in order that the blades of the leaves may lie principally outside the card initially at the stemming station as appears hereinafter. Preferably also, in order to effect a clean removal of the entire blade from its stem with a minimum impairment of the leaf structure, I provide a roller brush acting to spread the blades away from the stripper mechanism, i. e., the card or other device retaining the blade while the stem is extracted.

Another feature of importance is an inclined abutment or guide for the leaves at the entrance end of the machine to assure the proper positioning of the leaves with respect to the butting and/or stemming mechanism.

These and other features of my invention are shown in the accompanying drawings, from which, however, many details of the machine not concerned with my invention are omitted and others are merely indicated.

Fig. 1 is a plan view of a machine in which certain forms of my improvements are embodied.

Fig. 2 is a diagrammatic view in elevation of the system of belts of Fig. 1.

Fig. 3 is a fragmentary detail in elevation of the butting card clothing with its co-operating spring pressed holding plate; the card clothing and plate at the stemmer station are similarly arranged.

Fig. 4 is also a detail in vertical section taken on the line IV—IV of Fig. 1, drawn to a larger scale.

Fig. 5 is a further vertical detail of the stripping mechanism taken on the line V—V of Fig. 1.

Fig. 6 is a plan view of a second machine embodying certain modifications of my invention.

Fig. 7 is an elevation thereof, the supporting table structure being omitted.

Fig. 8 is a sectional side view at the stemming station of Fig. 6.

Referring first to Figs. 1 to 5: The table 1, forming part of the general supporting structure of the machine, need not be described in detail. In general it embodies cross members and side frame members 2 and 3 which serve to support the various instrumentalities hereinafter described, including driving shafts 4, 5, and 5^a, provided with gears which may be actuated from any suitable source of power, and various idler pulleys or rolls supporting the belts hereafter mentioned. Around one pair of rolls 6 and 7, of which the roll 6 is fast on the shaft 4, runs an endless belt 8 having riveted to its rear edge an endless card-clothed belt 9 which forms part of the butting mechanism to be described. At 10 is another card-clothed belt having carding wires or teeth 11 which may be somewhat wider spaced, this card-clothed belt being riveted to a belt 12 which runs upon the rollers 13 and 14, the latter being driven by the shaft 5. The belt 10 constitutes part of the stripping mechanism at the stemming station.

Other belts may be provided for the requisite feeding and holding of the leaves B, and several such belts are shown, being designated by the reference characters 15, 16, 17, 18, 19 and 20, and reference will be made to these belts as occasion requires. In the present machine, all the belts, including the card-clothings, move continuously at the same uniform speed in a direction to carry the leaves from left to right in the drawings.

At 77 at the entrance end of the machine is a vertical guide which is here a stationary plate. The operator lays the leaves on the conveyor belts 15 and 16 with the butts of the stems against the guide, as shown at b¹ in Fig. 1: if the leaves are very long, they will extend onto the conveyor belt 17. The function of a guide plate is to assure the proper placing of the leaves with respect to the butter and stemmer, and for this purpose it is so located that a leaf placed on the conveyor belts with the end of its stem against the guide will be operated on by both the butting brush and the stem extracting mechanism. It has been found however that the operators are frequently careless and frequently fail to place the stem ends fully against the guide. To overcome this difficulty I have here inclined the guide to the front, that is to say, the left hand end of the guide is placed farther from the front of the machine (i. e., farther from the frame member 3) than the right hand end, and the latter is properly located to introduce the leaves to the butting mechanism. If now the operator lays a leaf with its stem not quite against the guide, the travel of the leaf with the conveyor belts will bring it against the guide

ultimately and the latter will then properly position the leaf on the belts.

The butter 30 is a roller brush of suitable structure set at a slight angle to the travel of the conveyor belts 16 etc., and preferably having a bevelled leading end 31 to permit the leaves passing easily underneath it. It is shown mounted on a shaft 32 rotatable in a bearing 33 carried by the frame member 2, and having a gear wheel 34 driven by a chain 35 which may be connected in any suitable manner with the driving mechanism of the machine. The roll 30 is mounted to rotate above a stationary butting surface 36, preferably flat, and which may be a part of the table top 1, elevated if necessary as indicated by the shoulder 37 (Fig. 1) to bring the level of the surface 36 approximately flush with the upper surface of the card-clothed butting belt 9 (see Fig. 4). The brush in rotating presses the leaf stems against the surface 36 and sweeps off any fragments of blade, etc. that may be on them while the leaf as a whole is held fast on the conveyor belt 16 by upper belt 18, assisted or not by the card 9, but the principal function of the card-clothing 9 is to exert sufficient traction on the stems to carry them over the table surface 36 and underneath the brush while the latter is operating. The direction of rotation of the brush 30 is indicated by the arrow in Fig. 4. At 38 is a narrow plate serving to cause the leaves to enter the card clothing 9 and to hold them therein. To facilitate the entrance of the leaves this plate may be upturned at its entrance and (left-hand end) and may be slightly inclined downwardly so as to approach closest to the card toward its exit end (see Fig. 3). Preferably the plate is mounted pivotally at 39 upon a bracket 40 carried by the frame member 2 and its free end pressed downwardly by a spring 41 carried by a bracket 42, so that the rear portion of the member 38 is held yieldingly against the ends of the wires of the card-clothing 9. From adjacent the point 44 on the table (or surface 36) a stationary wire or wires 46 extend to the other side of the stemming mechanism. The butted portions of the leaves b² slide on top of this wire, and the latter thus supports the ends of the stems while the stems are passing across the gap between the table and the card-clothing 10, and assists in introducing the stems into this card-clothing.

The wire or wires 46 lie between parallel rows of the wires or teeth of the upper run of the card-clothing 10. This card-clothing 10, it will be observed, is a separate unit from the card-clothing 9 and is placed further to the rear (closer to frame member 2) than the clothing 9, so that while it receives the cleaned butts of stems b² of the leaves leaving 9 and the butting mechanism, the blades of the leaves are substantially entirely in front of and outside the clothing 10. The butts how-

ever project beyond the rear edge of the card-clothing 10 (the right-hand edge in Fig. 5). Above the top run of the card-clothing 10 is a holding plate 45, substantially like plate 38, which is mounted pivotally upon a bracket 48 carried by the frame member 2 while its free end 49 is spring-pressed toward the card-clothed stripping belt 10 by means which may be identical with the parts shown at 41 and 42 in Fig. 3. This end 49 of the holding plate is broken away in the illustration however, and its spring bracket omitted for the sake of clearness in illustration. While the leaves are being carried sidewise with the stems projecting from the card 10, the stems pass between the cooperating belts 50 and 51 (Figs. 1 and 5), the adjacent faces of which travel to the rear (to the right in Fig. 5) substantially parallel to the length of the stems. These belts are set close enough together to grasp the stems firmly and pull them to the rear, and further are of such width and travel at such a speed that the stems are completely extracted while the leaves are passing in front of them, the blades of the leaves being retained by and more or less bunched up against the wires of the cards. I find that the stems may be adequately extracted by such belts although the apparent tendency of the conveyors and cards on the one hand, and the belts 50 and 51 on the other, are to carry the blades and stems at right angles to each other. The belts 50 and 51 are mounted on pulleys 52 and 53 and other pulleys keyed to the shafts 56 and 57, and are driven at equal speeds by the interconnected gears shown, and by the chain 58, which is connected to a power source on the machine. These pulleys, it will be observed, face the conveyors and stripping means, that is to say, their axes are substantially parallel to the edges of the belts 20, etc. and the card 10, so that the adjacent faces or runs of the belts 50 and 51 travel almost directly at right angles to the travel of the conveyors, and preferably the bite plane of the belts is substantially coincident with the plane of the card and conveyors (Fig. 5). It is not necessary however that the pulleys be exactly parallel to the edges of the conveyor and card belts, as shown in Fig. 1, and there is some advantage in locating them at some angle to these edges as hereafter explained; nor is my invention limited to a single pair of belts for extracting the stems, although as illustrated a single pair suffices. At b^3 and b^4 I show successive stages of bunching up of the blades; b^5 indicates a stem entered between the belts and b^6 a stem being ejected. The belts may be of some rather soft elastic material, such as a rubber covered canvas, so as to accommodate both large and small stems and also so as to be able to grasp and exert some traction on the middle of the stems or veins and even farther on toward their tips, as well as on the butts which are larger than

the tips. To the same end the pulleys 52 and 53 may be covered with or composed of some fairly soft or elastic material as represented by the rubber surfacing at 53'. The shaft 53 may be mounted in fixed position and the shaft 52 have means at both ends providing adjustable yielding pressure downward as indicated at 55. I have also provided a mounting for the shafts 56 and 57 which is well adapted to the present purposes. The shaft 56 is carried in fixed bearings, not shown, adjustable fore and aft to tighten the belt 51. The shaft 57, however, is mounted in brackets 59 carried on blocks 60 which slide on rockers 62 pivoted at 63 on the brackets 64. These extend upward from the frame at 54 and have adjusting bolts 65 to limit the movement of the rockers 62. A set screw 61 in a slot in block 60 serves to secure the block to its rocker, and another, 66, serves to push the slide 60 outward and tension the belt 50. Since the pivot 63 is above the belt 50, it will be observed that the tension of the belt 50 acts to press this belt down against the belt 51. The single adjustment of the screws 66 therefore (one at each side of the belt), serves not only to change the tension of the belt 50 but also to change the pressure of the belt 50 on the cooperating belt 51. As stems are drawn between the belts however the upper belt 50 may rise at either end as the thickness of the stems demand.

To aid in stripping off the blade, I have shown at 70 a roller brush mounted upon a shaft 71 which is journaled in arms 72 (one is omitted from the illustration). These arms are carried by the brackets 64 and the brush is driven by a chain 73 running to a gear 74 upon the shaft 56; the brush turns in the direction indicated by the arrow in Fig. 5. The brush strikes the leaves just in front of the plate 45, as indicated in Figs. 1 and 5, where, it will be observed, it tends to spread out the blades of the leaves during the stripping operation, and facilitate the stripping action.

After leaving stemming station the blades are received underneath the belt 20 which presses them somewhat against the belt 19, pulling them loose from the card belt 10 as the latter turns down and carrying them off the right-hand end of the machine. The wire or wires 46 may also assist in releasing the blades from the card 10, into which the blades are ordinarily pulled somewhat, and for this purpose this wire extends to the right beyond the pulley 13 as shown in Fig. 1.

Referring now to Figs. 6, 7 and 8, which show another machine embodying certain modifications of my invention: As in the preceding figures, there is a table or general supporting structure 1 with side frame members 2 and 3 and supporting end rolls 80 and 81 to carry the conveyor belts 82 and 83 which extend the entire length of the machine; these

belts also extend around the rolls 84 and 85 underneath the table, and the roll 84 is usually the driven roll which causes the belts to move continuously at a uniform rate. In this 5 modification the guide at the entrance end of the machine is in the form of a vertical belt 86 mounted on rollers 87 which may be driven in any suitable manner so that the forward or leaf-engaging face of the belt 86 travels 10 in the same direction and at the same speed as the conveyor belts. A fixed vertical supporting plate 90 may be used to support this front run of the belt 86, which is inclined to the front like the guide 77 of the preceding 15 figures, that is to say, the right hand end of this forward run of the belt 86 is closer to the main conveyors and frame member 3 than the lefthand end. The belt 86 thus serves to assure the proper placing of the leaves on the 20 conveyor mechanism, and inasmuch as it travels along on the conveyors and leaves I regard it as preferable to a fixed guide. No butting mechanism is shown in the machine of these 25 Figs. 6, 7 and 8 (although one may be used if desired, as illustrated in Fig. 1) for I have found that the endless belts which I use for grabbing and pulling out the stems are adequate for extracting the stems even when the latter are not previously cleaned of blade 30 etc. Usually I also use a short flat belt 91, extending from the entrance end of the machine to the card belt at the butter, or at the stemming station, as the case may be, to support and carry the butt ends of the leaves; this may 35 be mounted on the rollers 80 and 92 and driven by the roller 80, which is driven by the belts 82 and 83. A smaller belt 93 may be placed still further to the rear, back of the belt 91, to further support the leaf butts; this 40 belt may be cylindrical (in cross section), and whatever its shape it may extend back of the leaf supports at the butting or stemming stations and thus bridge the gap between the belt 91 and these supports. This is illustrated in 45 the present machine where the belt 93 is placed back of the card-clothings 105 and 107 and is supported on the rollers 80 and 96, the latter being one of the rollers which supports the card clothing 105. 50 The mechanism for grasping and pulling out the leaf stems consists as before of two parallel belts 97 and 98. These belts, together with the mechanism which supports and drives them, are substantially like the belts 50 and 51 and the associated mechanism of the preceding figures. As before also, the stem-extracting belts are arranged substantially at right angles to the conveyor belts. However, with the stem extracting belts arranged exactly at right angles to the conveyor belts, as 55 illustrated in the preceding figures, there is a tendency for some of the leaf stems to bend over and follow along the belts 50 and 51 (from left to right) without entering their bite. To avoid this the stem extracting belts

may be somewhat displaced from the right angle relation previously described, so that while the forward end (left-hand end in Fig. 6) of the bite is properly located to receive the most protruding stems, the opposite (right-hand) end is located somewhat closer to the stripping means and conveyor, that is to say, the bite of the stem extractors is inclined forward or to the front. This is illustrated in Figs. 6 and 8, in which, it will be observed, the belts and pulleys 100, 101, 102 and 103 are inclined to the edge of the belt 82, approaching somewhat nearer the edge of the belt 82 at the exit (right-hand) end than at the opposite end, and in fact at their right hand ends the front rollers 100 and 101 respectively may slightly overhang and underhang the cards 107 and 105. This inclination of the belts 97 and 98 causes the stems to be carried deeper into mouth between the belts as it were, as they are carried sidewise by the conveyor mechanism and cards 105 and 107 of the stripping mechanism, and tends to insure the grabbing of the stems. Like the belts 50 and 51, the belts 97 and 98 are made of adequate width and are driven at adequate speed to extract those stems which fail to be grasped by the belts until after they have passed some distance along their mouth. Also like the belts 50 and 51, the belts 97 and 98 may be driven continuously at a uniform speed and pull out the stems while the leaves are moving sidewise.

The stripping mechanism in this modification contains a lower belt of card clothing 105 mounted on and driven by the rollers or pulleys 96 and 106, and in general resembling the card clothing 10 of Fig. 1 and its mounting. Underneath the upper run of the card clothing 105 may be a fixed cross member or table top 104 to maintain the clothing in position against any downward thrust upon it. Either one of the rollers 96 or 106 may be driven in any suitable way, so that the card clothing 105 travels at the same speed as the conveyor belts 82 and 83. However, in the place of the overlying plate 49 of the preceding figures, I prefer to employ a second or upper belt of card clothing 107 supported on suitable pulleys, such as 108, 109, 110, and 111, any one of which may be driven to move the belt 107 at the same speed as the card 105 (the adjacent runs of the two cards move in the same direction), or the card 107 may be driven by the engagement of its wires or teeth with the wires or teeth of the card clothing 105. The pulleys carrying the card 107 may be mounted on a suitable frame 113, and an adjustable plate 114 may be used to prevent the lower run of the clothing 107 from being thrust upward by the leaf blades between it and the lower clothing 105. Of the two lower pulleys, the lower entrance pulley 109 is placed slightly higher than the exit pulley 110, these two pulleys being so

arranged that the two card clothings are separated slightly at the entrance end, as shown in Fig. 7, but come together with their teeth or wires intermeshing opposite the belts 97 and 98. This permits the ready entrance of the leaves into the teeth or wires of the two card clothings where the blades will be retained while the stems are being extracted by the belts 97 and 98. The position, or even 10 the presence of the pulley 108 is an immaterial matter. The pulley 111, however, is preferably located somewhat to the rear (to the right in Fig. 7) of the exit pulley 110, so that the card clothing 107 departs from the lower 15 card 105 at an acute angle and faces downward in its run from its exit support to pulley 111. At this inclined run, I provide means for cleaning the clothing 107 as represented by the brush or drum 112 with projecting wires. This drum may be driven (preferably counter-clockwise in Fig. 7) in any suitable manner, as by the belt 116, and its bristles or wires penetrate between the wires 107 and thus sweep off the bits of leaf and 20 stem therein. These fall onto the clothing 105 in the present instance and are cast off the latter where the card 105 turns around the drum 106. Also I have provided a brush or wired drum 117 for similarly cleaning the 25 card 105. This cleaning brush or drum is likewise located underneath its card clothing, namely, in the present instance near the beginning of the lower run of the clothing 105. To strip the blades from the upper card 30 clothing, I have provided one or more wires or rods like 118, which has an upturned forward end 119 so that the leaves pass beneath it, and a horizontal straight length parallel with the lower run of the clothing 107 for 35 some distance of both sides of the pulley 110. As the clothing 107 moves upward therefore from pulley 110 toward pulley 111, the blades of the leaves are held down by the wire or wires 118 and thus extracted from the clothing 40 45 50 55 60 65 70 being withdrawn, said endless belt being set at such an angle to the leaf stems that the single belt and its cooperating surface suffice to extract the leaf stems.

5. In a leaf-stemming machine, blade retaining means, and a pair of endless belts adapted to receive the stems and draw the stems from the blades held by the blade-retaining means, said belts travelling substantially parallel to the length of the stems.

6. In a leaf-stemming machine, endless belt blade retaining means moving continuously and carrying the leaves bodily substantially sidewise, and a pair of co-operating 15 endless belts adapted to receive the butts therebetween and draw the stems from the blades retained by said means, said pair of belts travelling substantially at right angles to the movement of the blade retaining 20 means.

7. In a leaf-stemming machine, means to retain the blades, and a pair of endless belts adapted to receive the stems between themselves and draw the stems from the blades, 25 said belts being made of a somewhat soft material so as to accommodate stems of different diameters.

8. In a leaf-stemming machine, means to retain the blades, and a pair of endless belts 30 adapted to receive the stems therebetween and draw the stems from the blades, one of said belts being yieldingly supported to move bodily to and from the other belt.

9. In a leaf-stemming machine, means to retain the blades, a pair of endless belts 35 adapted to receive the stems therebetween and draw the stems from the blades, and means to support one of said belts comprising a plurality of shafts adjustable relative to each 40 other lengthwise of the belt to change its tension and a pivoted support for one of said shafts, the said one of the belts being between the pivot of said support and the other belt.

10. In a leaf-stemming machine, means to retain the blades, and a pair of endless belts 45 adapted to receive the stems therebetween and draw the stems from the blades, one of said belts having its intake end mounted upon a shaft yieldable to and from the intake end of the other belt, and having its delivery end mounted upon a shaft journaled upon a rocker mounted pivotally upon the frame of the machine, the said one of the belts being located between the pivot of said rocker and the other belt.

11. In a leaf-stemming machine, moving 50 blade-retaining means carrying the leaves bodily substantially sidewise, and means for grasping and pulling out the leaf stems while the leaves are being moved bodily sidewise, the bite of the last mentioned means being substantially parallel to the direction of movement of the first mentioned means.

12. In a leaf-stemming machine, moving 55 blade-retaining means carrying the leaves bodily substantially sidewise, and means for

engaging the stems to withdraw them substantially lengthwise from the leaf blades, a pair of oppositely-facing cooperating toothed belts to retain the blades while the stems are being withdrawn, one being superposed on the other, said superposed belt departing from the lower belt at an acute angle, and means acting on the superposed belt at this portion which is located at an acute angle to clean that belt. 70

13. In a leaf-stemming machine, the combination of superposed toothed belt members receiving the leaves and carrying them along, and means for extracting the leaves from the upper member comprising a wire-like member placed at one side of and extending to the exit end of said upper member and having its forward end raised so that the leaves pass underneath it. 80

14. For a leaf-stemming machine, butting 85 mechanism for leaves comprising a rotating roller brush rotating about a fixed axis, a substantially flat stationary surface against which the brush works the butts of the leaves, and a continuously moving toothed member receiving the leaves within its teeth and conveying the leaves between said brush and surface while the brush is in operation. 90

15. In a leaf-stemming machine, means to engage the stems and withdraw the same 95 endwise from the leaf blades, means to retain the blades and strip them from the stems, and a roller brush driven in a direction to brush the blades away from the blade-retaining means to spread the blades away from said blade-retaining means while the stems are being withdrawn. 100

16. In a leaf-stemming machine, means to engage the stems and withdraw the same endwise, means to retain the blade while the stems are being withdrawn comprising a pair of co-operating belts of card clothing, and means to drive one of said belts, the other of said belts being driven by the engagement 105 of its teeth or wires with the teeth or wires of the first. 110

17. In a leaf-stemming machine, means to engage the stems and withdraw the same endwise, means to retain the blade while the stems are being withdrawn comprising a pair of co-operating belts of card clothing, and means to drive one of said belts, the other of said belts being driven by the engagement of its teeth or wires with the teeth or wires of the first. 115

18. In a leaf-stemming machine, stemming mechanism comprising means for pulling out the stems and mechanism to retain the blades, conveyor mechanism for the leaves, a part of the conveyor mechanism terminating at the entrance to said blade-retaining mechanism, and a small belt located back of said conveyor mechanism and said blade-retaining 120 mechanism to support and carry the butts of the leaves to the stemming mechanism. 125

19. In a continuously operating leaf-stemming machine, a pair of cooperating belts having card clothing to engage the leaves and carry them laterally while the stems are being extracted, means to drive one of said belts continuously, the other of said belts being driven continuously by the engagement of its teeth with the teeth of the 130

belt driven by said means, and means to pull the stems from the blades while the leaves are being carried laterally by said belts.

20. In a leaf-stemming machine, stemming means comprising a pair of belts to engage and retain the leaf blades while the stems are being extracted and means to engage and pull the stems from the blades, a conveyor for the body parts of the leaves to carry the leaves to said stemming means, and a small belt located back of said pair of belts to carry the butts of the leaves to said pair of belts.

21. In a leaf-stemming machine, blade-retaining means, and a pair of endless belts adapted to receive the stems and draw the stems from the blades held by the blade-retaining means, said belts travelling at a very large angle to the direction of movement of the blade-retaining means.

22. In a leaf-stemming machine, continuously moving blade-retaining means carrying the leaves bodily substantially sidewise, and a pair of co-operating endless belts adapted to receive the butts therebetween and draw the stems from the blades retained by said means, the bite of said pair of belts being slightly inclined forwardly so that the end of said bite toward which the leaves approach is further from said blade-retaining means than the end of said bite from which the blades depart.

23. In a leaf-stemming machine, continuously moving blade-retaining means carrying the leaves substantially sidewise, and a co-operating endless belt and a surface adapted to receive the leaf butts for pulling the stems from the blades as the latter are retained by said means, said belt travelling nearly parallel to the lengths of said stems and having with said surface a bite which is slightly inclined forwardly.

24. In a leaf-stemming machine, the combination of means for retaining the blades, and means for pulling the stems from the blades, the bite of said pulling means being nearly at right angles to the length of the stems, but slightly inclined forwardly to the direction of movement of the leaves in approaching the bite.

25. In a leaf-stemming machine, the combination with stemmer means for grasping and extracting the stems from the blades, a transfer belt on which the leaves are laid by the operator and which convey the leaves toward said stemmer means, said belt permitting the leaves to be shifted thereon readily at the entrance end of the machine, and an inclined guide at the side of said transfer at the entrance end of the machine, said guide being inclined toward said transfer to correctly position the leaves on the transfer and said guide being a belt substantially at right angles to the transfer belt and moving

with and in the same direction as the transfer belt.

In testimony whereof, I have signed this specification.
